US0D1099806S

(12) **United States Design Patent** (10) **Patent No.:** **US D1,099,806 S**
(45) **Date of Patent:** **** Oct. 28, 2025**

(54) **WHEEL FOR AUTOMOBILE**

(71) Applicants: **Hyundai Motor Company**, Seoul (KR); **Kia Corporation**, Seoul (KR)

(72) Inventors: **Dae-Hwan Jo**, Gyeonggi-do (KR); **Seong-Ung Bae**, Gyeongsangnam-do (KR)

(73) Assignees: **Hyundai Motor Company**, Seoul (KR); **Kia Corporation**, Seoul (KR)

(**) Term: **15 Years**

(21) Appl. No.: **29/894,283**

(22) Filed: **Jun. 8, 2023**

(30) **Foreign Application Priority Data**

Jan. 16, 2023 (KR) 30-2023-0001785

(51) **LOC (15) Cl.** **12-16**

(52) **U.S. Cl.** **D12/209**
USPC **D12/209**
